AUTOMATIC FIRE PROTECTION SYSTEM
AND APPARATUS

Henry Ernest Heigis, West Orange, N. J., assignor
to Walter Kidde & Company, Inc., Bloomfield,
N. J., a corporation of New York

Application December 12, 1933, Serial No. 702,088

6 Claims. (Cl. 116—101)

This invention relates broadly to a system and apparatus for detecting and indicating or signaling the presence of fire, and embodies more specifically and improved heat actuated system and apparatus of the type referred to adapted for, but by no means limited to, use with vehicles propelled by internal combustion engines, such as airplanes, automobiles, tractors, and the like.

10 It is an object of the invention to provide a system and apparatus of the type referred to which is very simple in construction, neat in appearance, compact, economical to manufacture, effective in operation, and both easy to install and easy to service after operation.

15 It is another object of the invention to provide a system and apparatus of the type referred to for use with a self-propelled vehicle which will render a visible signal within the field of vision 20 of the operator of the vehicle.

25 These, and further objects of the invention not specifically enumerated above, will be apparent as the invention is described in greater detail in connection with the accompanying drawings, wherein:

30 Figure 1 is a view in side elevation of a fire detecting and indicating system constructed in accordance with the present invention and installed upon an airplane, a portion of which is shown in dot and dash lines.

Figure 2 is a view in front elevation of an indicating device in accordance with the invention, with a portion of the cover plate removed to show the interior construction.

35 Figure 3 is a view in section, taken on line 3—3 of Figure 2, and looking in the direction of the arrows.

Figure 4 is an external view of a heat actuator employed in the system of the present invention.

40 Referring to Figure 1, the reference numeral 1 represents an airplane of customary design having an engine 2, which it is desired to supervise against the outbreak of fire. For this purpose heat actuators 3, which form no part of the present invention but which are described in detail 45 in my copending application Serial No. 702,089, filed on even date herewith, are arranged at points where flames are likely to develop upon the outbreak of fire, such as at a point adjacent the 50 engine carburetor, in the oil pump, above the engine to the rearward thereof, etc. For the purpose of the present description it will be sufficient to understand that the heat actuators are of a type which are normally closed so as to 55 prevent fluid flow therethrough, but which are

opened upon the development of flames or sufficient heat so as to permit fluid flow therethrough. It will accordingly be noted that each of the heat actuators 3 serves to close a branch of the fluid conducting tubing 4, the latter of which is connected to an indicating device 5 mounted on the instrument panel 6 of the airplane and capable of rendering a visible indication upon the outbreak of fire. A second fluid conducting tubing 7 connects the indicating device 5 to the intake 10 manifold 8 of the engine 2, or to any other means for creating a degree of pressure different than atmospheric.

Referring now to Figures 2 and 3, in which the construction of the indicating device 5 is shown in detail, 9 represents a body member chambered at 10 and recessed at 11 to receive a sealing gasket 12 and a cover plate 13. Within the chamber 10, a turbine-like member 14 is provided, mounted by means of screws 15 on a flange 16 formed on a spindle 17 journalled at one end within a recess 18 of the body member 9 and journalled at the other end within a recess 19 of the cover plate 13. The vanes 20 of the turbine-like member 14 are arranged 25 within the chamber 10 so that there is only a relatively small clearance between the edges of the vanes and the defining walls of the chamber 10. The spindle 17 is provided with an enlarged center portion 21 provided with shoulders which 30 bear against the body member and the cover plate and which serve to center the turbine-like member within the chamber 10.

Passages 22 are provided in the body member 9, leading into the chamber 10 from the exterior of the body member, one of these passages being adapted to receive the fluid conducting tubing 4, and the other passage being adapted to receive the fluid conducting tubing 7, the 35 passages 22 being directed into the chamber 10 at such an angle as to discharge an operating fluid stream against the vanes of the turbine-like member 14 in order to effect rotation of said member 14.

The cover plate 13 is provided with a sight 45 opening 23, the latter being closed in an air tight manner by a transparent window 24, the purpose of which is to permit observation of the turbine-like member 14.

The turbine-like member may, of course, be 50 formed in any suitable manner, the member here shown being formed from a circular disc by slotting the same and twisting the segments formed into a position at right angles to the plane of the disc, thus forming the vanes 20.

- From the description thus far given, it will be apparent that when either the fluid conducting tubing 4 or the fluid conducting tubing 7 is connected to means for creating a degree of pressure different than atmospheric, the turbine-like member 14 will rotate in one direction or the other, depending upon whether the tubing is connected to a source of pressure or to a suction device; and it will be further apparent that, depending upon the degree of pressure difference and depending upon the construction of the turbine-like member, the turbine-like member will rotate at a speed which presents a different view through the transparent observation window 24 than when the member 14 is motionless. Thus, if the member 14 is rotated at a relatively low speed, its motion will be directly observable; whereas, if the member 14 is rotated at a relatively high speed, a continuous, blended or blurred yet distinctive indication will be given, which indication can be strengthened, for example, by suitable coloring of the edges of the vanes 20 and/or by spaced coloring of the flat central portion of the member 14.
- As described in connection with Figure 1, the fluid conducting tubing 4 is connected to one or more heat actuators 3, while the fluid conducting tubing 7 is connected to the intake manifold of the engine 2. When, therefore, the engine is operating without the use of the supercharger, if it has one, a suction will exist in the intake manifold 8; whereas, when the engine is operating with the supercharger, a positive pressure may exist in the intake manifold. In either event, the turbine-like member 14 of the indicating device 5 will not be operated so long as all of the heat actuators 3 are intact; but immediately upon the outbreak of fire and the opening of one or more of the heat actuators 3, a fluid flow will be established through the chamber 10 of the indicating device 5 in one direction or the other, depending upon whether the engine is operating with or without the supercharger.
- As the indicating device is mounted on the instrument panel of the airplane in full view of the pilot, the indication given thereby will warn the pilot and enable him to take whatever protective measures are necessary for the safety of himself and his plane.
- In the specific embodiment of the invention illustrated in Figure 1, the indicating device 5 has been shown connected to the intake manifold of an internal combustion engine, but it will, of course, be apparent that the indicating device may be connected in any other suitable manner, and is in fact equally operable when connected to any source of pressure greater or less than atmospheric, regardless of what may be the nature of source of pressure.
- While the foregoing description has dealt with one specific embodiment of the invention, it should be noted that the invention is capable of being carried out with other forms of construction, and I accordingly do not wish to be strictly limited to the disclosure, but rather to the scope of the appended claims.
- I claim:
1. In an automatic internal combustion engine fire protective system, the combination with the engine of an indicator operable by the continuous flow of a fluid, means on the engine to maintain a degree of pressure different from atmospheric pressure during the time of operation of the engine, a normally closed fluid system in-

cluding the indicator and the pressure maintaining means, and means for opening the fluid system to the atmosphere upon the outbreak of fire, said indicator comprising a body member formed with a chamber, inlet and outlet connections for connecting said chamber in said normally closed fluid system and for permitting a flow of fluid through the chamber, a movable element in said chamber adapted to remain normally motionless but to move continuously upon the creation of a flow of fluid through the chamber, and a sight opening for permitting observation of the movable element in either its motionless or its moving condition.

2. In an automatic internal combustion engine fire protective system, the combination with the engine of an indicator operable by the continuous flow of a fluid, means on the engine to maintain a degree of pressure different from atmospheric pressure during the time of operation of the engine, a normally closed fluid system including the indicator and the pressure maintaining means, and means for opening the fluid system to the atmosphere upon the outbreak of fire, said indicator comprising a body member formed with a chamber, inlet and outlet connections for connecting said chamber in said normally closed fluid system and for permitting a flow of fluid through the chamber, a movable element in said chamber adapted to remain normally motionless but to move continuously at a relatively high rate upon the creation of a flow of fluid through the chamber, and a sight opening for permitting observation of the movable element in either its motionless or its moving condition.

3. In an automatic internal combustion engine fire protective system, the combination with the engine of an indicator operable by the continuous flow of a fluid, means on the engine to maintain a degree of pressure different from atmospheric pressure during the time of operation of the engine, a normally closed fluid system including the indicator and the pressure maintaining means, and means for opening the fluid system to the atmosphere upon the outbreak of fire, said indicator comprising a body member formed with a chamber, inlet and outlet connections for connecting said chamber in said normally closed fluid system and for permitting a flow of fluid through the chamber, a movable element in said chamber adapted to remain normally motionless but to move continuously at a relatively high rate upon the creation of a flow of fluid through the chamber, indicating means associated with said movable element of a type presenting a contrast with the background thereof when motionless but presenting a continuous indicating appearance when moved at a relatively high rate, and a sight opening for permitting observation of the indicating means in either its motionless or its moving condition.

4. In an automatic internal combustion engine fire protective system, the combination with the engine of an indicator operable by the continuous flow of a fluid, means on the engine to maintain a degree of pressure different from atmospheric pressure during the time of operation of the engine, a normally closed fluid system including the indicator and the pressure maintaining means, and means for opening the fluid system to the atmosphere upon the outbreak of fire, said indicator comprising a body member formed with a chamber, inlet and outlet connections for connecting said chamber in said normally closed fluid system and for permitting a flow of fluid

through the chamber, a rotatable turbine-like element in said chamber adapted to remain normally motionless but to move continuously at a relatively high rate upon the creation of a flow of fluid through the chamber, and a sight opening for permitting observation of the turbine-like element in either its motionless or its moving condition.

5. In an automatic internal combustion engine fire protective system, the combination with the engine of an indicator operable by the continuous flow of a fluid, means on the engine to maintain a degree of pressure different from atmospheric pressure during the time of operation of the engine, a normally closed fluid system including the indicator and the pressure maintaining means, and means for opening the fluid system to the atmosphere upon the outbreak of fire, said indicator comprising a body member formed with a chamber, inlet and outlet connections for connecting said chamber in said normally closed fluid system and for permitting a flow of fluid through the chamber, a rotatable turbine-like element in said chamber adapted to remain normally motionless but to move continuously at a relatively high rate upon the creation of a flow of fluid through the chamber, indicating means associated with said turbine-like element of a type presenting a contrast with the background thereof at a plurality of positions when motionless but presenting a continuous indicating appearance when rotated at

a relatively high rate, and a sight opening for permitting observation of the indicating means in either its motionless or its moving condition.

6. In an automatic internal combustion engine fire protective system, the combination with the engine of an indicator operable by the continuous flow of a fluid, means on the engine to maintain a degree of pressure different from atmospheric pressure during the time of operation of the engine, a normally closed fluid system including the indicator and the pressure maintaining means, and means for opening the fluid system to the atmosphere upon the outbreak of fire, said indicator comprising a body member formed with a chamber, inlet and outlet connections 15 for connecting said chamber in said normally closed fluid system and for permitting a flow of fluid through the chamber, a rotatable turbine-like element in said chamber adapted to remain normally motionless but to move continuously 20 at a relatively high rate upon the creation of a flow of fluid through the chamber, indicating means associated with said turbine-like element comprising spaced coloring of portions of the turbine-like element presenting a contrast with 25 the background thereof when motionless but presenting a continuous-color indicating appearance when rotated at a relatively high rate, and a sight opening for permitting observation of the indicating means in either the motionless or 30 moving condition thereof.

HENRY ERNEST HEIGIS.
